UNITED STATES PATENT OFFICE

WILLIAM LE ROY BRYANT, OF SPRINGFIELD, VERMONT

GRINDING WHEEL

Original application filed July 20, 1921, Serial No. 486,080. Divided and this application filed December 26, 1925. Serial No. 77,838.

This invention relates to grinding wheels and is divided from my application Serial No. 486,080, filed July 20, 1921, and entitled "Grinding machine," which application issued as Patent No. 1,575,968, on November 9, 1926. An object of this invention is to provide a grinding wheel capable of grinding in one operation bars having different contours or portions of different diameters. 10 This requires a wheel with a broad face which may be the surface of a single abrasive member or of a number of members held side by side. The use of such wheels avoids handling the work more than once for the grinding 15 operation, and ensures accurate concentricity of different portions of the bar, which is not assured when the bar is subjected to successive grinding operations. The use of broad face grinding wheels, either of the same or different diameters, also offers advantages in both increased output and greater accuracy in production. This is accounted for on the score of increased production by the use of wheels with grinding faces 20 approximating the length of the work to be ground, so that an equal amount of stock may be removed simultaneously the full length of the work. It is apparent that the same amount of metal can thus be more quickly 25 removed than in the use of a narrow grinding face ordinarily employed, which must be arranged to travel back and forth across the work to be ground at such length as is required to cut over the entire length of the 30 work. This advantage applies both to the finishing of a long single diameter and to a combination of different diameters, but, in finishing pieces of different diameters, an added advantage is obtained from the fact 35 that the several diameters or sizes may be finished at one operation, thereby effecting the saving of the time required to change the pieces from one machine to another, or, if one operation follows another in the same machine, the elimination of making of necessary 40 adjustments on the grinding machine. There is also an advantage in accuracy in the finishing of several diameters at one operation, in that all surfaces thus finished are concentric and true with each other, a condition which 45 may or may not be so, as the work is moved in and out of the machine in making the several operations one at a time. Even though a bar is to be ground so as to have the same diameter from end to end, I find it desirable 50 to employ a sectional grinding wheel, as the reciprocation of the work makes it possible to prevent the formation of corrugations or irregularities on the periphery of the work. By employing relatively narrow sections, they 55 can be combined together in axial relation to produce a grinding tool having the breadth of face desired. For instance, in the grinding of a bar of twelve-inch length, I may use six two-inch width wheels clamped together, 60 or four three-inch wheels mounted side by side. The use of a limited reciprocation or longitudinal traverse for the work carrier permits the use of a wheel so mounted, as the side motion of the work serves to eliminate 65 any marks that might be made by the joints in the grinding wheels. An economic advantage is secured in the use of narrow wheels 70 in making up a broad face, on the score of its being unnecessary to keep in stock wheels to 75 cover a variety of lengths of work. For instance, if there were pieces six-inch, eight-inch, ten-inch and twelve-inch length to be ground in different lots, by using one broad wheel it would be necessary to carry a wheel 80 for each length. By the use of the narrow wheels, say of two-inch and three-inch width, a combination of different widths can be used to make up the total length needed, making a great deal smaller the wheel investment required. Also, due to the usual method of 85 building up the abrasive material, it is easier to construct a narrow face grinding wheel without variation in the hardness or abrasive qualities of the grinding material through- 90

out, than by the use of one wheel of greater face and area.

In the drawings,—

Fig. 1 represents a longitudinal section through one form of my improved grinding wheel and a part of the mechanism supporting the same;

Fig. 2 represents in longitudinal section a portion of a grinding wheel having a single cylindrical face of the same diameter from end to end;

Figs. 3 to 6 illustrate different forms of the work and the respective wheels which may be utilized in finishing the same, each figure representing a portion of a grinding wheel and the work to be ground thereby.

Referring to Fig. 1 in detail, the shaft 65 which carries and turns the grinding wheel is journaled in a bushing 76 set in a carriage, portions of which are indicated at 75 and 78. Suitable ducts are provided to ensure proper lubrication of the bearings. At one end the grinding wheel shaft 65 is provided with a flange 83 and a reduced portion 84 to which the hub of the grinding wheel may be removably bolted or otherwise secured. Preferably the machine is provided with a plurality of interchangeable grinding wheels for operating upon work of different kinds. Each wheel may with convenience comprise a hub 85 having an internal projecting flange 86 which may be bolted or otherwise secured to the flange 83 of the shaft 65. The flange 86 encircles the reduced end 84 of the shaft, and between them is placed a hardened steel bushing 87. The hub of the grinding wheel may with convenience be made of aluminum or other suitable material. The grinding wheel proper, or that portion which is employed for grinding the work, is annular and is clamped between an undercut flange 88 projecting radially from the hub and a removable clamping member 89, which is likewise undercut and which is secured to the face of the hub by screws 90. In the form shown in Fig. 1, I provide three grinding or abrading members 91, 92, 93, all of which are of different diameters and which may be of different kinds of grinding material if desired. Between these members are provided additional spacing and clamping members 94, 95. The flange 88, the clamp 89, and the spacers 94, 95, form dove-tail annular grooves into which complementary portions of the abrading or grinding members are clamped. The dove-tail construction enables the clamping and spacing rings 94, 95 to grip the inner portions of the rings in such a way as to anchor each portion of the ring against radial motion and thus to oppose positively centrifugal reaction on the rings regardless of the integrity of the rings. Unless so anchored, each portion of a ring depends on tensile strength of all the rest of the ring, and if the ring is cracked or weak

in one place, it is liable to fly in pieces from the hub when rotated at grinding speeds. In Fig. 2, I have shown the hub 85 as provided with a single abrading or grinding member 96 which is provided with a cylindrical exterior of the same diameter from end to end. It will be observed that in this case the member is of such axial length that it projects to some extent beyond the end of the hub, and consequently I employ a clamp 97 having an elongated hub portion 98 to accommodate the abrading or grinding member. Instead of a single cylindrical abrading member 96, a plurality of disks 96' of equal diameter may be employed, as indicated in Fig. 3. These grinding members may take different forms according to the character of the operation to be accomplished. In Figs. 3 to 6, inclusive, I have shown portions of different grinding members which may be utilized. In addition to those shown in Figs. 3 and 4, I have shown one member 99, in Fig. 5, which is double tapered, and another member 100, in Fig. 6, the face of which is concave. From these Figs. 3 to 6, inclusive, it will be seen that, by these respective grinding or abrading members, the work may be finished or ground in different forms.

Referring once more to Fig. 1, it will be observed that the grinding wheel, considered as a whole, is enclosed within a water guard 101 which rests upon a straight flange 102 formed on the portion 78 of the carriage. As a matter of construction, anti-friction balls 107 may be located between the guard 101 and the flange 102 to support the weight of the guard and make it easy to adjust the guard. The guard is provided with a face cover 108. The construction and arrangement of these and other related parts of the grinding machine are fully described in my application Serial No. 486,080, previously referred to.

What I claim is:

1. A grinding wheel comprising a hub having an undercut peripheral flange and an undercut clamping member, undercut spacing rings on said hub between said flange and clamping member, forming therewith a plurality of dove-tail grooves, and a plurality of abrasive rings or sections having dove-tail inner portions complementary to and clamped in said grooves.

2. A grinding wheel comprising a hub having at one end an undercut peripheral flange, a clamping member at the other end thereof constituting a continuation of said hub and having an undercut peripheral flange, a plurality of abrasive rings undercut to form dove-tail inner portions seated on said hub and clamping member, and locking rings seated on said hub between consecutive abrasive rings, said locking rings being complementary to said dove-tail inner portions of the abrasive rings.

3. A grinding wheel comprising a hub, a plurality of abrasive rings mounted on said hub, and locking rings loosely mounted on said hub and clamped between successive abrasive rings for positively opposing centrifugal reaction on each portion of said abrasive rings.

In testimony whereof I have affixed by signature.

WILLIAM LE ROY BRYANT.
